(57) **CLAIM**

The ornamental design for a watercraft tower, as shown and described.

DESCRIPTION

FIG. 1 is a top, left side perspective view showing a new design of a watercraft tower;

FIG. 2 is a top, right side perspective view thereof;

FIG. 3 is a bottom, right side perspective view thereof;

FIG. 4 is a bottom, left side perspective view thereof;

FIG. 5 is a right side view thereof;

FIG. 6 is a left side view thereof;

FIG. 7 is a front view thereof;

FIG. 8 is a rear view thereof;

FIG. 9 is a top view thereof; and,

FIG. 10 is a bottom view thereof.

The dash-dash broken lines illustrate portions of the watercraft tower that form no part of the claimed design. The dash-dot broken lines depict a boundary of the claim and forms no part of the claimed design.

1 Claim, 8 Drawing Sheets
